DESIGN FOR A DRESS

Albert Ruchman, New York, N. Y.

Application January 26, 1937, Serial No. 67,289

Term of patent 3½ years

To all whom it may concern:

Be it known that I, Albert Ruchman, a citizen of the United States of America, residing in Manhattan, county of New York, and State of New York, have invented a new, original, and ornamental Design for a Dress, of which the following is a specification, reference being had to the accompanying drawing, forming part thereof, wherein,

The design is characterized by the arrangement of the lace yoke on the front and back collar portions and the lace inserted godet on the sleeves, in combination with the dress, as shown.

I claim:

The ornamental design for a dress, substantially as shown, and described.

ALBERT RUCHMAN.
